UNITED STATES PATENT OFFICE.

PHILIP C. ENGEL, OF MINNEAPOLIS, MINNESOTA.

DESIGN FOR A PIE PLATE.

Application filed November 13, 1926. Serial No. 19,717. Term of patent 7 years.

To all whom it may concern:

Be it known that I, PHILIP C. ENGEL, a citizen of the United States, residing at Minneapolis, in the county of Hennepin and State of Minnesota, have invented a new, original, and ornamental Design for Pie Plates, of which the following is a specification, reference being had to the accompanying drawing, forming part thereof.

Figure 1 is a plan view and Figure 2 is a central vertical section of a pie plate, showing my new design.

I claim:

The ornamental design for a pie plate, as shown.

PHILIP C. ENGEL.
